[57] **CLAIM**

The ornamental design for a two handle faucet, as shown and described.

DESCRIPTION

FIG. 1 is a front perspective view of a two handle faucet showing my new design;

FIG. 2 is a rear perspective view thereof;

FIG. 3 is a top plan view thereof;

FIG. 4 is a front elevational view thereof;

FIG. 5 is a right side elevational view thereof, the left side being a mirror image;

FIG. 6 is a rear elevational view thereof; and

FIG. 7 is a bottom plan view thereof;

FIG. 8 is a cross-sectional view of the escutcheon taken along line 8—8 in FIG. 1;

FIG. 9 is a cross-sectional view of the escutcheon taken along line 9—9 in FIG. 2; and,

FIG. 10 is a cross-sectional view of the escutcheon taken along line 10—10 in FIG. 2.

The broken line showings of the aerator in FIGS. 1-2, 4-5 and 7, and of the handles in FIGS. 1-7 are for purposes of illustration only and form no part of the claimed design.
